UNITED STATES PATENT OFFICE.

HORACE S. GORDON, OF DAYTON, OHIO.

PUMP FOR DISPENSING OIL.

No. 868,981.

Specification of Letters Patent.

Patented Oct. 22, 1907.

Application filed November 12, 1906. Serial No. 342,896.

To all whom it may concern:

Be it known that I, HORACE S. GORDON, a citizen of the United States, residing at Dayton, in the county of Montgomery and State of Ohio, have invented certain new and useful Improvements in Pumps for Dispensing Oil; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in oil-dispensing pumps, and the improvements relate to means for registering and indicating the specific quantities and the total quantity of oil dispensed.

The object of the invention is to provide simple and efficient means in connection with registering and indicating devices, whereby the operations or rather the quantities of oil dispensed during the operations, are registered and indicated at points adjacent to the main operating shaft of the pump.

The essential features of the invention will be hereinafter described in the specification and specifically pointed out in the annexed claims.

Preceding a detailed description of the invention, reference is made to the accompanying drawings, of which—

Figure 1, is a front elevation of the entire apparatus, parts of the casing being broken away to show the pump mechanism proper. Fig. 2, is a detail sectional view of the detail register devices, on line $x-x$ of Fig. 1. Fig. 3, is a rear view in detail of the disk of the detail registering devices and the worm on the crank shaft operating therewith. Fig. 4, is a detail of the rear side of the indicating dial. Fig. 5, is a view of the outer side of the actuating disk shown in Fig. 3. Fig. 6, is a sectional view on the line $y-y$ of Fig. 1. Fig. 7, is a sectional view on the line $v-v$ of Fig. 1. Fig. 8, is a top plan view of Fig. 7. Fig. 9, is a detail view of the flange which interlocks with the hub of the crank handle. Fig. 10, is a side elevation of the upper portion of the pump.

In a detail description of the invention, similar reference characters indicate corresponding parts.

The frame-work and pump mechanism are not comprised in the invention and will be only incidental mentioned. The frame-work 1 comprises a stand which incloses the pump cylinder 5 and the co-operating mechanism all of which is located below the upper frame-work 2 and 3 mounted upon said lower frame-work 1. The crank shaft 4 is mounted in bearings 6 and 7 on the upper end of the frame 3; fast upon said crank shaft 4 is a crank wheel 8 which is coupled to a connecting link 9 which in turn, is connected with the piston rod 10 of the pump.

The detail register consists of a movable dial 11 graduated with the proper numerals and index marks to indicate the specific quantities of oil dispensed in gallons and multiples thereof; this detail register comprises in connection with the dial 11; a disk 12, the outer side of which is provided with ratchets 13 adapted to engage with ratchets 14 on the inner face of the dial 11 to impart movement to said dial when the pump is being operated. It will be understood that the ratchets 14 engage the ratchets 13 when the disk 12 is being operated from the crank shaft, and that the said ratchets 14 ride freely over the ratchets 13 when the dial 11 is turned to zero and is thus given movement independently of the disk 12. The dial 11 and disk 12 are loosely mounted upon shaft 14' which is rigidly attached to an arm 15 extending at right angles from the frame 3. On the outer end of the shaft 14' in the front of the dial 11 there is a stationary pointer 16 to which the dial is moved in the operations of the pump and when a predetermined amount of oil has been discharged from said pump, after which the said dial is set to zero as shown in Fig. 1.

Suitable contact is maintained between the ratchets 14 and 13 by means of a spiral spring 18 inclosed between the pointer 16 and the outer face of the dial. The rear face of the disk is provided with a concentric row of pins 17 which are engaged by a worm 19 on the crank shaft, said worm being fixed thereon. It will be seen that movement is imparted in this manner to the disk 12 and thence to the dial 11 through the ratchets; the operation of the detail register takes place as before stated, upon each operation of the pump. A complete rotation of the crank shaft discharges a specific quantity of oil, for example, one gallon, and such quantity will be indicated upon the dial 11 at the pointer 16. Any less movement of the crank shaft will dispense and indicate quantities less than gallons; the index marks between the gallon marks on the dial, indicating quarts as said dial is graduated in the present instance. A total counter 95 of well known construction is also provided at the crank shaft for registering the entire contents of the pump or the entire quantity of oil dispensed from the pump for any given length of time; this total register 100 is mounted upon the bearing 7 of the frame 3 and is connected with the crank shaft 4 through chain wheels 21 and 22, one of which is fast on the crank shaft, and the other of which is fast on the projected end of the shaft of the counter—see Figs. 1 and 6, said chain wheels being connected by a chain 23 through which the movement is imparted from the crank shaft to the counter shaft. The connections between the hub 26 of the crank handle, and the crank shaft 4 through which the latter is rotated, are as follows: The hub 26 turns loosely on the shaft until it is engaged with the disk 28, which engagement is effected through means of a spring-pressed dog 29 seated in an opening in the

hub 26. The adjacent face of the disk 28 is provided with a recess forming a shoulder 30 at one end thereof with which the dog 29 engages when the crank handle is rotated in its operative direction, and when said crank handle is rotated in the reverse direction, the dog 29 rides freely over the surface of the disk 28. The disk 28 has a hub 31 which is fixed to the crank shaft 4. Upon a complete rotation of said disk and shaft, a signal is given indicating a complete revolution of the crank shaft, said signal being due to the click of a spring-pressed plunger 25 moving into engagement with a tapered recess 24 in the outer end of the shaft bearing 7. The spring-pressed plunger 25 is located in an opening in the hub 31, and one side of the notch 24 is tapered to match the end of the plunger 25 so as to permit said plunger to ride out of the notch when the crank shaft is rotated in the operations of the pump. It will thus be seen that any reverse movement of the crank handle 27 will not affect the shaft 4 owing to the dog 29 riding freely over the face of the disk 28 during such movement.

I claim:

1. In a pump for dispensing oil, a crank shaft having a worm gear thereon, a dial mounted upon an inclination

in the front of said worm gear, said dial having on its rearward side a series of spaced ratchets, a disk mounted in the rear of and parallel with the dial and rotatable upon a common axis with the dial, said disk having on its outer face a series of ratchets adapted to engage the spaced ratchets on the dial, and a series of pins on the rearward side of said disk engaging the worm gear on the crank shaft, and a stationary pointer mounted in front of the dial, substantially as set forth.

2. In a pump for dispensing oil, the combination with a crank shaft having a worm gear thereon, a detail indicating dial to denote the specific quantities of oil dispensed, said dial having upon its rearward side a series of ratchets, a disk mounted in the rear of and parallel with said dial, said disk having on its outer side a series of ratchets engaging the ratchets on the dial, and upon its rearward side a series of pins engaging the worm on the crank shaft, a fixed pointer in front of the dial, and a total counter connected with the crank shaft and adapted to record the total of the oil dispensed from the pump and indicated on the dial in specific quantities, substantially as set forth.

In testimony whereof I affix my signature, in presence of two witnesses,

HORACE S. GORDON.
